United States Patent [19]

Skogler et al.

[11] Patent Number: Des. 300,312

[45] Date of Patent: * Mar. 21, 1989

[54] COMBINED REARVIEW MIRROR AND LIGHT UNIT

[75] Inventors: Brian I. Skogler, Spring Lake; William W. Gallmeyer, Holland, both of Mich.

[73] Assignee: Donnelly Corporation, Holland, Mich.

[*] Notice: The portion of the term of this patent subsequent to May 26, 2001 has been disclaimed.

[**] Term: 14 Years

[21] Appl. No.: 836,610

[22] Filed: Feb. 27, 1986

[52] U.S. Cl. D12/188

CLAIM

The ornamental design for a combined rearview mirror and light unit, as shown and described.

DESCRIPTION

FIG. 1 is a rear perspective view of a combined rearview mirror and light unit showing our new design;

FIG. 2 is a rear elevational view thereof;

FIG. 3 is a front elevational view thereof;

FIG. 4 is a top plan view thereof;

FIG. 5 is a bottom plan view thereof;

FIG. 6 is a left side elevational view thereof;

FIG. 7 is a right side elevational view thereof;

FIG. 8 is an enlarged side sectional view thereof taken along line VIII—VIII of FIG. 2;

FIG. 9 is a rear perspective view of a second embodiment of the combined rearview mirror and light unit;

FIG. 10 is a rear elevational view of the second embodiment;

FIG. 11 is a front elevational view of the second embodiment;

FIG. 12 is a top plan view of the second embodiment;

FIG. 13 is a bottom plan view of the second embodiment;

FIG. 14 is a left side elevational view of the second embodiment;

FIG. 15 is a right side elevational view of the second embodiment;

FIG. 16 is an enlarged side sectional view of the second embodiment taken along line XVI—XVI of FIG. 10.
